UNITED STATES PATENT OFFICE.

EDUARD H. MASON, OF WHITE MARSH, VIRGINIA.

HAT-PIN GUARD.

1,168,528.

Specification of Letters Patent. Patented Jan. 18, 1916.

Application filed June 27, 1913. Serial No. 776,005.

To all whom it may concern:

Be it known that I, EDUARD H. MASON, a citizen of the United States, residing at White Marsh, in the county of Gloucester and State of Virginia, have invented certain new and useful Improvements in Hat-Pin Guards; and I do hereby declare the following to be a full, clear, and exact description of the invention, such as will enable others skilled in the art to which it appertains to make and use the same.

This invention relates to a hat pin guard, the object thereof being to provide a device adapted to be secured upon the pointed end 15 of a hat pin, to retain the hat pin in place, and also to guard against the point of the pin penetrating or scratching adjacent persons or objects.

A further object is to provide an improved protecting sleeve for the hat pin guard to prevent a veil or the trimming of the hat from becoming damaged by contact with said guard.

Improved details in the construction and arrangement of the various parts of the invention will be apparent from the detailed description hereinafter when read in connection with the appended claim, reference being had to the accompanying drawing 30 forming part hereof, in which,

Figure 1 represents a side elevation of the improved hat pin guard, showing the application thereof to a hat pin. Fig. 2 represents an enlarged sectional view there-35 through, with the parts in position for the insertion or removal of the pin. Fig. 3 represents a side elevation of the hat pin guard having the protecting device therefor removed, and, Fig. 4 represents an end view 40 of the guard as shown in Fig. 3, and Fig. 5 is a view similar to Fig. 2 with the guard in closed position.

Referring specifically to the drawings, 1 indicates a pin provided with a flared head 2, and a circumferential groove 7 near its point.

3 indicates the guard proper, tubular throughout the greater portion of its length, and provided with a flared and closed rear 50 or outer end, at 4, and a flared and open forward or inner end, at 5, being also longitudinally slotted, at 8, from the end 5 to sub-

stantially its midlength, thus forming resil- 55 ient tongues. An inner annular rib 6 is formed, crossing the tongues, to engage, by the resiliency of the tongues, in the groove 7 of the pin, to retain the pin in the guard (as shown) in Fig. 2. To prevent the accidental 60 removal of the pin from the guard and to prevent the hair, a veil, or hat trimmings being caught on the slotted end of the guard, I provide a protector tube 9 which is slid- 65 ably mounted over the guard. The pro- 70 tector tube is of a diameter at its end 10^a to snugly fit over the tongues and that part of the guard slightly beyond the beginning thereof, is flared at its opposite end 10 and has the edge of its flared end turned inward 75 to protect the ends of the tongues.

When the parts are in the positions shown in Fig. 2, with the end 10^a of the protector tube fitting on the guard beyond the slits, the pin may be entered or removed, the tongues 75 yielding outwardly to permit of its passage, and the rib 6 engaging in or sliding out of groove 7 by the resiliency of the tongues.

After the pin has been entered in the guard 3 and the annular rib 6 seated in the circum- 80 ferential groove 7 and the protecting tube 9 is moved longitudinally of the guard until the flared inner face of the end 10 thereof en- 85 gages the flared end 5 of the guard and the end 10^a is positioned nearer the rib 6, out- 90 ward movement of the resilient tongues will be prevented, making it impossible under ordinary circumstances to remove the pin from the guard until the protector tube is again moved outwardly on the guard so as to re- 95 lease said tongue. When the protector is thus moved to hold the tongues against yielding, the flared turned in end 10 will protect the slotted end of the guard in the manner specified. The protector tube is 95 prevented from leaving the guard 3 by the flared ends of the resilient tongues.

What I claim is:

A hat pin protector comprising a tubular member having a closed flared outer end and 100 an open flared inner end, and slotted from the inner flared end to about its mid length, to form tongues, said tongues being trans- 105 versely grooved forming an inwardly pro- jecting annular rib, and a protecting sleeve 105 slidably mounted upon the tubular member,

having one end portion of a diameter to snugly fit upon the slitted portion of the tubular member and slightly beyond the slits and its other end flared, projecting beyond the tongues and turned inward to protect the slitted end of the tubular member.

In testimony whereof I have signed my

name to this specification in the presence of two subscribing witnesses.

EDUARD H. MASON.
